Primary Examiner — Darlington Ly(74) *Attorney, Agent, or Firm* — SCHWEGMAN
 LUNDBERG & WOESSNER, P.A.(57) **CLAIM**

The ornamental design for a motorcycle as shown and described.

DESCRIPTION

FIG. 1 is a front and left side perspective view of a motorcycle embodying our new design;
 FIG. 2 is a front elevation view thereof;
 FIG. 3 is a rear elevation view thereof;
 FIG. 4 is a right side view thereof;
 FIG. 5 is a left side view thereof; and,
 FIG. 6 is a top plan view thereof.

The broken lines in the drawings illustrate portions of the motorcycle that form no part of the claimed design.

1 Claim, 6 Drawing Sheets# US D1,101,625 S
